United States Patent Office

JERESIAH D. EGLESTON, OF CANAAN, CONNECTICUT.

Letters Patent No. 81,991, dated September 8, 1868.

IMPROVED MEANS FOR SECURING SPRINGS FOR BEDS AND SEATS.

The Schedule referred to in these Letters Patent and making part of the same.

TO ALL WHOM IT MAY CONCERN:

Be it known that I, JERESIAH D. EGLESTON, of Canaan, in the county of Litchfield, in the State of Connecticut, have invented a new and improved Mode of Securing Springs in Beds and Seats; and I do hereby declare that the following is a full and exact description thereof, reference being had to the accompanying drawings, and to the letters of reference marked thereon.

The nature of my invention consists in securing a coiled cone-spring to a slat or bottom of a bed or seat, by means of a screw-nut, cut into said slat or bed or seat-bottom, into which said spring is fitted as a screw.

To enable others skilled in the art to make and use my invention, I will proceed to describe its construction and operation.

Into a slat, or any board, or piece of wood, designed for the bottom of a bed or seat, I bore a hole, and cut it out as for a nut to a screw, into which I fit the small end of a single cone-coiled spring, as shown at A in the accompanying drawing, the wire of the spring answering as a thread, holding the spring and slat together.

Springs thus secured are applicable to beds and seats of all kinds that the common sofa-springs are, and may be covered and used in the same way, or in any other convenient manner.

I make a bed of slats about four inches wide, made into sections of two, three, or four slats in each, cleated at the ends, into which I set the springs, having them occupy a space of seven inches, more or less, each, thus completing it, ready for a mattress on top of the springs; or I use the slats on top of the springs, each one separate, with two or more springs to a slat, with the large end of the spring down, and secured to or placed upon an arm, or transverse slats underneath.

What I claim as my invention, and desire to secure by Letters Patent, is—

The screw-nut A, combined with the spring B, substantially as and for the purpose set forth.

JERESIAH D. EGLESTON.
